UNITED STATES PATENT OFFICE

144,026

DESIGN FOR AN AIRPLANE

Herbert L. Bowers and Robert A. Wolf, Kenmore,
N. Y., assignors to Bell Aircraft Corporation,
Buffalo, N. Y.

Application April 9, 1942, Serial No. 106,502

Term of patent 14 years

(Cl. D71—1)

To all whom it may concern:

Be it known that we, Herbert L. Bowers and Robert A. Wolf, citizens of the United States, residing at Kenmore, county of Erie, State of New York, have invented a new, original, and ornamental Design for an Airplane, of which the following is a specification, reference being had to the accompanying drawings, forming a part thereof.

Figure 1 is a top plan view of an airplane showing our new design;

Figure 2 is a front elevational view;
Figure 3 is a side elevational view; and
Figure 4 is a rear elevational view thereof.

We claim:

The ornamental design for an airplane, as shown.

HERBERT L. BOWERS.
ROBERT A. WOLF.
